(57) **CLAIM**

The ornamental design of a control handle with a display for an endoscopic device, as shown and described.

DESCRIPTION

FIG. 1 is a top view of an embodiment of a control handle with a display for an endoscopic device;

FIG. 2 is a right side view of the embodiment of FIG. 1, the left side view being a mirror image thereof;

FIG. 3 is a perspective view of the embodiment of FIG. 1 with the display shown in a closed position; and,

FIG. 4 is a perspective view of the embodiment of FIG. 1 with the display shown in an open position.

The portion of the article shown in broken lines in FIGS. 1-4 is for illustrative purposes only and forms no part of the claimed design.
